US00D745495S

(12) **United States Design Patent**
Fereday et al.

(10) **Patent No.:** US D745,495 S
(45) **Date of Patent:** ** Dec. 15, 2015

(54) **MICROPHONE CAPSULE MOUNT**

(71) Applicant: **Freedman Electronics Pty Limited**,
Silverwater NSW (AU)

(72) Inventors: **Tom Ferghana Rogers Fereday**,
Silverwater NSW (AU); **Samuel Dean Trewartha**, Silverwater NSW (AU)

(73) Assignee: **Freedman Electronics Pty limited**,
Silverwater, New South Wales (AU)

(**) Term: **14 Years**

(21) Appl. No.: **29/473,533**

(22) Filed: **Nov. 22, 2013**

(30) **Foreign Application Priority Data**

Nov. 14, 2013 (AU) 15864/2013

(57) **CLAIM**

The ornamental design for a microphone capsule mount, as shown and described.

DESCRIPTION

FIG. 1 is a front view of a microphone capsule mount, showing our new design;

FIG. 2 is a side view of the design;

FIG. 3 is a rear view of the design;

FIG. 4 is a side view of the design;

FIG. 5 is a top view of the design; and,

FIG. 6 is an isometric view of the design.

The broken lines on the body of the microphone capsule mount in FIGS. 2, 4, and 6 depict parts of the microphone capsule mount that form no part of the claimed design; the circular capsule on top of the mount shown in broken lines in the figures depicts environmental subject matter and forms no part of the claimed design.

1 Claim, 6 Drawing Sheets
